UNITED STATES PATENT OFFICE.

ROBERT R. THEISS, OF HOUSTON, TEXAS.

CASING SHOE.

Application filed October 2, 1923. Serial No. 686,081.

This invention relates to new and useful improvements in a casing shoe.

One object of the invention is to provide a shoe of the character described specially designed for the purpose of reinforcing pneumatic tire casings at points where the casing may be weak, and designed also for use in said casings where blowouts have occurred.

Another object of the invention is to provide a shoe of the character described which may be secured around the inner tube of a casing and placed opposite a blowout or weak point in the casing and which will be held in position by the tube and will not creep around the casing.

A further object of the invention resides in the provision of a shoe of the character described which is formed of novel means for fastening the same on the inner tube of the tire.

With the above and other objects in view the invention has particular relation to certain novel features of construction, operation and arrangement of parts, an example of which is given in this specification and illustrated in the accompanying drawings, wherein:

Figure 1 shows a perspective view of the shoe in open position.

Figure 2 shows a side view thereof secured around the inner tube and,

Figure 3 shows a cross sectional view taken on the line 3—3 of Figure 2.

In the drawings the numeral 1 designates the inner inflatable tube of a pneumatic tire, the numeral 2 designates the shoe as a whole. This shoe is formed of a substantially rectangular body composed of two or more plies of rubberized fabric, an inner ply as

3 and an outer ply as 4. A greater number of plies may be used if desired. The plies are constructed of strong fabric material preferably rubberized. The ends of the body are somewhat narrower than at 45 the center so that when fastened around the tire tube the ends of the shoe will firmly grip the tube, when the latter is inflated to prevent the creeping of the shoe.

In one edge of the shoe there are the long 50 slots 5 and at the other edge the outer ply 4 is formed with interlocking tenons as 6 adapted to be drawn through the corresponding slots 5, said tenons being formed with lateral wings or extensions which 55 interlock with the slotted edge of the shoe, as shown in Figure 2, so as to hold the shoe secured around the inner tube. The shoe is secured in place while the tube is deflated and when the same is placed in the casing 60 and inflated the shoe will thereby be securely held in proper position.

What I claim is:—

A casing shoe adapted to surround the inner tube of a pneumatic tire and formed 65 of two plies of flexible fabric material, one edge of the shoe being formed with slots, tenons carried by the other edge of the outer ply of said shoe and adapted to be inserted through said slots, said tenons 70 having lateral wings which engage with the slotted edge of said shoe, the corresponding edge of the inner ply being extended and underlying the joints formed between said tenons and slots, the ends of the shoe being 75 contracted to securely grip said tube when the latter is inflated.

In testimony whereof I have signed my name to this specification.

ROBERT R. THEISS.
